UNITED STATES PATENT OFFICE.

GEORGE C. MOORE AND THOMAS F. MOORE, OF WESTERLY, RHODE ISLAND.

DESIGN FOR AN ELASTIC WOVEN FABRIC.

Application filed August 18, 1922. Serial No. 3,453. Term of patent 14 years.

To all whom it may concern:

Be it known that we, GEORGE C. MOORE and THOMAS F. MOORE, citizens of the United States, residing at Westerly, in the county of Washington, State of Rhode Island, have invented a certain new, original, and ornamental Design for Elastic Woven Fabric, of which the following is a specification, reference being had therein to the accompanying drawings.

Fig. 1 is a view of a portion of elastic woven fabric, showing our new design.

Fig. 2 is an enlarged photographic view

of such fabric, on a somewhat enlarged scale, and showing details more clearly than they are shown in Fig. 1.

We claim:

The ornamental design for elastic woven fabric, as shown.

In testimony whereof we affix our signatures, in presence of two witnesses.

GEORGE C. MOORE.
THOMAS F. MOORE.

Witnesses:

BERNICE PRESCOTT,
ELLA LEIPER.
